Robert J. Rettman, Pittsburgh, Pa., assignor to Jas. H. Matthews & Co., Pittsburgh, Pa., a corporation of Pennsylvania

Application November 17, 1954, Serial No. 33,133

Term of patent 14 years

(Cl. D79—2)

Fig. 1

The memorial plaque is characterized by the particular border effect and the specific arrangement of the foliage thereon.

I claim:

The ornamental design for a cemetery memorial plaque or the like, substantially as shown and described.
